UNITED STATES PATENT OFFICE

168,092

EGG CUP OR SIMILAR ARTICLE

Jon Hedu, Watertown, Conn., assignor to The Watertown Manufacturing Company, Watertown, Conn., a corporation of Connecticut

Application July 18, 1952, Serial No. 20,668

Term of patent 14 years

(Cl. D44—9)

To all whom it may concern:

Be it known that I, Jon Hedu, a citizen of the United States, residing in Watertown, county of Litchfield and State of Connecticut, have invented a new, original, and ornamental Design for an Egg Cup or Similar Article, of which the following is a specification, reference being had to the accompanying drawing, forming part thereof, in which

Fig. 1 is a perspective view of an egg cup or similar article showing my new design;

Fig. 2 is a perspective view of the lower portion of the cup;

Fig. 3 is a side elevational view thereof; and

Fig. 4 is a bottom plan view of the cup.

I claim:

The ornamental design for an egg cup or similar article, substantially as shown.

JON HEDU.
